AUTOMATIC OVEN LIGHTER

Peter I. Hollman and Stanley H. Hobson, Rockford, Ill., assignors, by mesne assignments, to The Cleveland Trust Company, Cleveland, Ohio, a corporation of Ohio

Application November 1, 1929, Serial No. 404,184
Renewed October 2, 1937

8 Claims. (Cl. 158—115)

This invention relates to an automatic oven lighter and is an improvement upon that type claimed in the application of Frank A. Gauger, Serial No. 332,896, filed January 16, 1929.

Automatic lighters have been applied to gas stoves for several years operating on the flash-back principle that is described, for example, in Methudy Patent No. 1,675,899, issued July 3, 1928, according to which principle, when the gas for a burner is turned on, some gas is conducted through a tube to a pilot light where it is ignited and the ignition flashed back through the tube to the burner. Such automatic ignition was thoroughly practical for the cooking top burners, owing to their close proximity to the pilot light, but the automatic ignition of the oven burner has not been satisfactorily taken care of. The difficulty there we found to be attributable chiefly to two things. In the ordinary stove the tube extending from the oven burner to the lighter had to be pretty long, and when the oven burner was turned on it took too much time for the gas to flow through this tube to the lighter and flash back, the oven being almost filled with gas in the meantime so that there was a perceptible puff upon ignition of the oven burner. In the case of stoves equipped with oven regulators, the amount of gas supplied to the tube from the oven burner obviously depended on the setting of the regulator, and at low temperature settings there was apt to be insufficient gas supplied to the tube extending to the lighter for a flash-back to occur, and, consequently, ignition was very uncertain, and here again, the fact that the lighter tube had to be so long was, of course, a factor that contributed to unsatisfactory ignition. It is, therefore, the principal object of our invention to provide an automatic oven lighter which is not only quicker in its action, so as to eliminate the objectionable puffing, but is, moreover, absolutely positive in its operation under all conditions and not affected in its operation by the amount of gas supplied to the oven burner itself, so as to be operable just as definitely when the oven burner is turned on part way as when it is turned on all way.

According to our invention, an intermediate burner is provided between the oven burner and the lighter, having a tube extending therefrom to the lighter, said burner being arranged to have gas supplied thereto when the oven cock is open, and being arranged to be lit just as easily and quickly as a cooking top burner, and arranged, in turn, to light the oven burner. The intermediate burner is made very small and con-

serves very little gas, and serves as a pilot light for the oven burner, arranged to ignite said burner in the event the oven regulator cuts down the flow of gas to the burner to a point where the same is apt to be extinguished. It is also preferred to have the intermediate burner project part way from the side wall of the oven where the flame thereof will be visible from in front of the stove, so that one can be certain when this burner is lit that there will be no question as to the lighting of the oven burner.

The invention is illustrated in the accompanying drawing, in which—

Figure 1 is a phantom view of a gas stove showing the oven burner thereof provided with an automatic lighter in accordance with our invention;

Fig. 2 is an enlarged longitudinal vertical section on the line 2—2 of Fig. 1;

Fig. 3 is a transverse vertical sectional detail on the line 3—3 of Fig. 2;

Fig. 4 is an enlarged sectional detail through the valve controlling the flow of gas to the automatic oven lighter, and

Fig. 5 is a view similar to Fig. 3 showing a modified or alternative construction.

The same reference numerals are applied to corresponding parts throughout the views.

Referring to Fig. 1, the stove illustrated has the usual cooking top 5 next to the oven section 6. None of the cooking top burners is shown, but the oven burner appears at 7. The manifold 8 has the oven cock 9 connected to the underside thereof and communicating with the burner 7 through an oven regulator 10 in any suitable or preferred manner. We show an elbow 11 connected to the cock 9 and communicating with the pipe 12 leading up to the regulator 10, and another pipe 13 extending downwardly from the regulator to the usual mixer 14 provided on the inlet end 40 of the oven burner. 15 is the thermostat of the regulator 10, and 16 is the control lever, the setting of which determines the temperature maintained in the oven in the usual way, that is, the thermostat causes the closing of the valve of the regulator more or less when the temperature reaches a predetermined high point, and opens the valve of the regulator more or less when the oven temperature drops to a predetermined low point, depending on the particular mean temperature which it is desired to maintain and for which the lever has been set. The stove thus far described is purely conventional.

The automatic igniter or lighter shown at 17 is similar to that disclosed in the Methudy patent

referred to above, and is suitably disposed in the center of the cooking top between the burners thereof. It has tubes 18 radiating from the hollow central body 19 for communication with the pilot light 20, the tube 21 of which is connected with the manifold 8 through a suitable control valve 22. As indicated above, when any one of the cooking top burners is turned on, gas issuing from a port on the burner flows through the tube 18 to the pilot light and ignites, causing a flash-back to the burner to ignite the latter. There was no difficulty in the automatic ignition of the cooking top burners, owing to the proximity of these burners with the igniter. The tubes 18 could, therefore, be fairly short and it took little time for the gas to reach the igniter from the burner for the flash-back to occur. However, the attempt to light the oven burner with a simple tube has not proved practical or at least not generally satisfactory. In the case of the ordinary stove, it took too long for the gas to flow through the long tube from the oven burner all the way to the igniter, and by the time the flash-back occurred, the oven was usually partly or nearly filled with gas and the result was that a loud puff would be heard when the burner was ignited. In case the broiler door happened to be open, flame would be thrown from the stove at the moment of ignition, which, of course, was more or less objectionable. Stoves equipped with oven regulators presented a still further difficulty in that the flow of the gas to the burner was apt to be cut down by the regulator to such an extent that insufficient gas would be delivered to the tube for a flash-back to occur, and consequently, the ignition was rendered very uncertain. The automatic oven lighter 23 made in accordance with our invention is designed to avoid the objections noted and make the automatic ignition of the oven burner just as quick and certain as the ignition of the cooking top burners.

The automatic oven lighter 23 consists of an elongated cast iron burner 24 extending into the oven 6 to a point immediately alongside the oven burner 1, through a hole 25 in a cast iron ring 26 arranged to be suitably secured on the oven wall as by means of screws 27. The hole 25 is oblong as shown in Fig. 3, and the burner 24 fits in the upper portion thereof and is fastened in such position by means of a lug 28 cast integral therewith which has a screw 29 passed through a hole therein and threaded in a lug 30 cast integral with the ring 26. The burner 24 is slotted longitudinally on the underside thereof, as shown at 31, there being sufficient space below the burner in the hole 25 for the flame projected downwardly from the burner when the same is lit. A combustible mixture of gas and air is supplied to the burner through a Bunsen tube 32 attached to the burner outside the oven, as shown. A flexible tube 33 for supplying gas to the tube 32 has connection with the elbow 11 through a control valve 34. Adjustment of the screw 35 on said valve determines the amount of gas delivered to the automatic lighter 23. A tube 36 extends from the outer end of the burner 24 to the automatic igniter 17. The tube is preferably fastened rigidly to the end of the burner 24 in a collar portion 37 cast integral with the end of the burner. The tube has this end spaced slightly from the end of the burner so that when gas is injected therein from a port 38 provided in the end wall of the burner, air is entrained with it to form a combustible mixture. The other end

of the tube has a sliding fit in a neck 39 preferably cast integral with the body 19.

The burner 24, instead of being disposed in the upper portion of the hole 25 and having the slot 31 on the underside thereof, may be disposed in the lower part of the opening 25 with the longitudinal slot 31 on the upper side thereof, as shown in Fig. 5. This arrangement, as a matter of fact, presents certain slight advantages over the other arrangement. For example, it is thought it facilitates the lighting of the burner by the flash-back, owing to the fact that the gas flowing through the slot 31 rises in one heavy stream instead of being possibly divided into two streams. Furthermore, the flame from the burner is more easily visible with the burner disposed in this position.

In operation, when the oven cock 9 is opened, gas is delivered to the burner 24, and a certain amount of this gas issues from the port 38 and is conducted along with air entrained therewith through the tube 36 to the pilot light 20 for ignition. A flash-back occurs, resulting in the ignition of the burner 24 the full length of the slot 31, and the oven burner 1 is ignited from the burner 24, the inner end of the latter being close to the side of the oven burner so as to be sure to ignite the gas issuing from the ports provided in the underside of said burner. The fact that there is such a short line of communication between the burner 24 and the oven cock 9 as compared with the line of communication between the oven burner 1 and the oven cock, makes it reasonably certain that, even allowing for the slight delay for the automatic ignition of the burner 24, the burner 24 will be ignited before any gas has issued from the oven burner and the latter will, therefore, be ignited as soon as enough gas issues therefrom. It is well known that the regulator 10 is set for any desired oven temperature, and that the oven cock 9 is always opened fully as a matter of course. Hence, it is easy to understand that the burner 24 will always have a definite amount of gas supplied thereto irrespective of the amount of gas supplied to the oven burner. The automatic ignition is, in other words, unaffected by the amount of gas supplied to the oven burner. The oven burner is usually ignited practically as quickly as any cooking top burner because there is no perceptible delay in the ignition of the oven burner from the burner 24, and the latter, it is evident, is ignited just as quickly as a cooking top burner. The burner 24 will obviously always maintain the same sized flame, regardless of the control of the oven burner by the regulator 10, so that it is arranged to serve as a pilot light for the oven burner. When the regulator 10 cuts down the flow of gas to the oven burner, the flame is frequently brought so low that it is extinguished, and a pilot light for igniting the same again when the flow of gas to the burner is resumed, is, therefore, a necessity. Ordinarily a special pilot light had to be provided for the oven burner, but that is made unnecessary where our invention is used, so that a certain saving is effected. The fact that the burner 24 extends from the oven a certain amount is an advantage from the standpoint that one can always see the flame of this burner from in front of the stove and in that way be certain that the oven burner is ignited. However, it should be noted that our improved lighter is automatic in its action so long as the hand cock 9 is turned on, since the intermediate burner burns continuously by an independent

charge of gas regardless of the setting of the oven regulator and, in any event, should the intermediate burner be extinguished it will be re-ignited by gas discharging through the port 38 into the flash-back tube or flame conducting conduit 36 and being ignited by the remote igniting device which in the present illustration is in the form of a constantly burning pilot light.

It is believed the foregoing description conveys a thorough understanding of our invention. The appended claims are drawn with a view to covering all of the features described in terms broadly enough to afford protection on all legitimate modifications and adaptations, such as will 15 no doubt occur to those skilled in the art as a result of this disclosure.

We claim:

1. In a gas stove, an automatic oven burner lighter comprising, a constantly burning pilot remote from the oven, a pilot burner in proximity to the oven burner for directly igniting the same, means for supplying gas to the oven burner controlled by a valve, means for charging the oven pilot burner with gas by opening movement of 25 said valve and continuing said charge so long as said valve remains open, means for supplying primary air to the gas being delivered to said oven pilot burner, and a flash-back conduit between said remote pilot burner, and said oven 30 pilot burner adapted to be charged with a mixture of gas and air delivered from said oven pilot burner, whereby said oven pilot burner will be ignited by flash-back from the remote pilot and will in turn ignite the oven burner, and whereby 35 said oven pilot burner continues to burn so long as the oven burner is being supplied with gas and will automatically re-ignite the oven burner in the event said oven burner is extinguished by gas pressure drop or by accident.

2. In a gas stove, an automatic oven burner lighter comprising, a constantly burning pilot remote from the oven, a pilot burner in proximity to the oven burner for directly igniting the same, means for supplying gas to the oven burner controlled by a valve, means for charging the oven pilot burner with gas by opening movement of 45 said valve and continuing said charge so long as said valve remains open, means for supplying primary air to the gas being delivered to said oven pilot burner, and a flash-back conduit between said remote pilot burner and said oven pilot burner adapted to be charged at its end remote from the constantly burning pilot with a mixture of gas and air delivered from said oven 50 pilot burner, whereby said oven pilot burner will be ignited by flash-back from the remote pilot and will in turn ignite the oven burner, and whereby 55 said oven pilot burner continues to burn so long as the oven burner is being supplied with gas and will automatically re-ignite itself as well as the oven burner in the event either or both said burners is extinguished by gas pressure drop or by accident.

3. In a gas stove, an automatic oven burner lighter comprising, a constantly burning pilot light remote from the oven, an oven pilot burner in such proximity to the oven burner that gas issuing from the oven burner will be directly ignited by the flame of the oven pilot burner, and a flash-back conduit for lighting the oven 65 pilot burner by propagation of flame in said conduit ignited by said constantly burning remote pilot light, the oven pilot burner being continuously supplied with gas at all times while gas is supplied to the oven burner, whereby said oven 70

pilot burner remains constantly burning for re-igniting the oven burner should the latter be extinguished.

4. In a gas stove, an automatic oven burner lighter comprising, a constantly burning pilot 5 light remote from the oven, an oven pilot burner in such proximity to the oven burner that gas issuing from the oven burner will be directly ignited by the flame of the oven pilot burner, and a flash-back conduit for lighting the oven 10 pilot burner by propagation of flame in said conduit ignited by said constantly burning remote pilot light, the oven pilot burner being a Bunsen burner having an orifice supplied with a combustible mixture of gas and air, said oven pilot 15 burner orifice being arranged to deliver said mixture into the end of said flash-back conduit remote from the constantly burning pilot.

5. In a gas stove, an automatic oven burner lighter comprising, a constantly burning pilot 20 remote from the oven, a pilot burner in proximity to the oven burner for directly igniting the same, means for supplying gas to the oven burner controlled by a valve, an oven regulator interposed in said gas supply means between said valve and 25 the oven burner for regulating the temperature of the oven, means for charging the oven pilot burner with gas by opening movement of said valve and continuing said charge so long as said valve remains open, means for supplying primary 30 air to the gas being delivered to said oven pilot burner, and a flash-back conduit between said remote pilot burner and said oven pilot burner adapted to be charged with a mixture of gas and air delivered from said oven pilot burner, 35 whereby said oven pilot burner will be ignited by flash-back from the remote pilot and will in turn ignite the oven burner, and whereby said oven pilot burner continues to burn so long as the oven burner is being supplied with gas and will 40 automatically re-ignite the oven burner in the event said oven burner is extinguished by gas pressure drop or by accident.

6. An oven lighter comprising an elongated burner arranged to be mounted in the side wall 45 of an oven of a gas stove so as to project into proximity with the oven burner, means whereby said burner is supported in the side wall of the oven, the outer end of said burner having a port provided therein, a flash-back tube extending 50 from this end of the burner and so disposed relative thereto to have gas delivered thereto from said port along with air entrained therewith, said tube being arranged to have communication at its other end with a pilot light for automatic ignition purposes, and means for supplying gas to 55 said burner.

7. In a gas stove, in combination, an oven compartment having an oven burner, a pilot light remote from the oven compartment, a burner in 60 the oven compartment in proximity to the oven burner for lighting the same, a Bunsen mixer for supplying a mixture of gas and air to said lighting burner, a flash tube extending from said remote pilot light to a point in proximity to said 65 lighting burner, said lighting burner having a port for discharging gas into the adjacent end of said flash tube, said port and adjacent end of the flash tube being located outside of the oven burner compartment.

8. In combination, a gas burner, a compartment in which said burner is located, a pilot light remote from said compartment, a lighting burner located in said compartment in proximity to the first-mentioned burner for lighting the same, a 75

flash-back tube extending from said remote pilot light to a point in proximity to said lighting burner for lighting the lighter, means for supplying gas to the first-mentioned burner and to the lighting burner, and means whereby gas from the lighting burner is charged into the adjacent end of the flash-back tube, said means being located outside

of said burner compartment and serving to entrain air into the flash tube from an area unaffected by the heat and circulation effects of the burner compartment.

PETER I. HOLLMAN.
